CLAIM

The ornamental design for an adjustable hooded robe, as shown and described.

DESCRIPTION

FIG. 1 is a perspective view of an adjustable hooded robe showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another front elevational view in the condition of use thereof; and,

FIG. 9 is another perspective view in the condition of use thereof.

The broken lines throughout the drawing figures depict portions of the adjustable hooded robe that form no part of the claimed design.
